ROCK DRILLING APPARATUS

Elmer G. Gartin, Claremont, N. H., assignor to
 Sullivan Machinery Company, a corporation of
 Massachusetts

Application December 12, 1928
 Serial No. 325,630

25 Claims. (Cl. 121—19)

My invention relates to improvements in rock drilling apparatus.

An object of my invention is to provide an improved streamline design of a rock drilling machine. A further object is to provide an improved valve mechanism for a rock drill. Still another object of my invention is to provide an improved stopper rock drill of compact streamline design having an improved valve mechanism. A still further object of the invention is to provide an improved tubular valve mechanism surrounding the rifle bar in axial alinement with the hammer cylinder and providing means for allowing an unrestricted flow of motive fluid to the cylinder on its power stroke. Other objects and advantages of the invention will appear during the course of the following specification.

In the accompanying drawings I have shown for purposes of illustration two embodiments 20 which my invention may assume in practice.

In these drawings,—

Fig. 1 is a central longitudinal sectional view through a stopper rock drill embodying my invention, the ends of the machine being cut away.

Fig. 2 is a view similar to Fig. 1, but showing the moving parts in a different position.

Fig. 3 is a fragmentary sectional view through a portion of the valve chest on line 3—3 of Fig. 4.

Fig. 4 is a transverse sectional view through the valve chest section on line 4—4 of Fig. 1.

Fig. 5 is a longitudinal sectional view of a portion of the mechanism on line 5—5 of Fig. 4 with parts shown in elevation.

Fig. 6 is a fragmentary sectional view through one of the throw passages on line 6—6 of Fig. 4.

Fig. 7 is a central longitudinal sectional view through a modified form of my invention, showing the same as applied to a drifter type of drill.

Referring to Figs. 1 and 2, there is illustrated a stopper rock drill of generally well known design having a hammer cylinder 1, a feed cylinder 2, an intermediate head member 3, a valve chest section 4, and a chuck housing 5, all arranged in longitudinal alinement and held together by suitable side rods which are indicated in section at 6 and 7 in Fig. 4. These side rods are engaged with collars 8 and 9 at their opposite ends, which collars engage shoulders 10 and 11 on the feed cylinder and chuck housing respectively. A hammer piston 12 reciprocates in the cylinder 1 and has a striking bar 13 which is arranged to hammer on a tappet 14 and through this tappet the blows are transmitted to the shank 15 of the drill steel loosely mounted in the chuck housing.

A common type of automatic rotation mechanism driven by the piston is provided for rotating the drill steel. This rotation mechanism 60 comprises a ratchet and pawl mechanism 16

mounted in the head member 3 having a rifle bar 17 extending forwardly through the valve chest section 4 into a central bore in the piston. A rifle nut 18 is threaded into the piston and has the usual spiral flutes cooperating with spiral lugs on the rifle bar to cause relative oscillatory movement between the piston and rifle bar upon reciprocation of the piston. The piston is thereby intermittently rotated and this rotative movement is transmitted by straight cooperating grooves and lugs on the piston extension 13 and chuck nut 19 secured in a chuck 20 which forms a driving connection with the drill steel.

Instead of the usual reciprocating valve mounted in a valve chest projecting laterally from the hammer cylinder, my invention provides a valve chest formed in axial alinement with the hammer cylinder in the section 4 rearwardly of the hammer cylinder. This construction eliminates the large lateral projection necessitated by the usual lateral valve chest and at the same time provides means permitting a direct axial flow of motive fluid to the rear end of the hammer cylinder on the power stroke of the piston. The valve chest is provided with a plurality of bores 21 and 22 in which are slidably received cylindrical portions or spools 23 and 24 respectively of the valve. At the forward end of the valve chest there are provided two annular inlet grooves 25 and 26 separated by a partition 27 for guiding the valve. This provides for an ample and unrestricted flow of motive fluid through the valve chest and at the same time provides adequate means for supporting the end of the valve during its reciprocating movement.

When the valve is in the position shown in Fig. 1, one of the inlet grooves is arranged to communicate directly with the rear end of the cylinder through a large axial passage 28, and the forward end of the cylinder communicates by way of passages 29 and 30, as shown in Fig. 5, with an annular groove 31 in the valve chest, and this groove is adapted to be connected by a groove 32 in the valve to the inlet groove 25 when the valve is in the position shown in Fig. 2, the supply motive fluid to the forward end of the cylinder. The annular groove 31 in one position of the valve is also adapted to be connected to exhaust by the annular groove 32 on the valve, which places it in communication with the annular exhaust groove 33 which connects directly to atmosphere through suitable exhaust ports 34. A throw passage 35, as best shown in Fig. 6, leads from the cylinder to the bore 21 in the valve chest at a point rearward of the flange 23. The valve also has a shoulder 36 presenting a rearwardly facing area which is subjected to constant pressure by means of a constant pressure passage 37 which communicates with the inlet as will be later described. Projecting rearwardly from the shoul-

der 36 on the valve is a tubular extension 38 slideable in a bore 39 so as to guide the end of the valve and seal the constant pressure chamber. The bore 39 is formed in an intermediate bearing section 40 disposed between the head member 3 and valve chest section 4. This member forms a suitable support and bearing for the ratchet mechanism and rifle bar. The valve is provided with axial bores 41 and 42 in which the rifle bar is freely rotatable. The valve presents three areas in constant communication with the rear end of the cylinder, namely, the areas on each end of the valve and the area formed by the shoulder 43 between the bores 41 and 42. One or more central exhaust ports 44 open through the cylinder wall and form the sole exhaust for the rear end of the cylinder and the main exhaust for the front end.

Referring now to Fig. 4, motive fluid is supplied to the machine through a connection 45 at one end of the throttle valve casing 46 in which is rotatably mounted a conical throttle valve 47. This valve is provided with a large axial passage 48 and means including a V-shaped groove 49 for conducting motive fluid to the large inlet passage 50. This inlet passage is in direct communication with both of the annular inlet grooves 25 and 26, a portion of the flange 27 being cut away adjacent the inlet port. The constant pressure passage 37 communicates directly with the inlet passage 50 as shown in Fig. 3 and pressure is thus applied to the shoulder 36 whenever motive fluid is being supplied to the drill. Suitable means are also provided to give a constant supply of live fluid pressure to the forward end of the drilling mechanism for blowing the hole. This means comprises a groove 51 formed on the surface of the throttle valve communicating with the central inlet passage 48 by a short passage 52 and in one position of the valve, as shown in Figs. 1 and 2, this groove is placed in communication with a longitudinally extending passage 53 formed in the valve chest section and cylinder wall, which in turn leads to an angular passage 54 formed in the front cylinder head or buffer member 55. This conducts the live pressure fluid to the straight grooves in the striking bar 13 and from this point the fluid flows through the grooves to the chamber 55' which is always in communication with the bore in the drill steel by means of the axial passage 56 in the tappet 14. The usual means may be provided for supplying also a cleansing liquid to the bore of the drill steel which in this instance comprises a central liquid conducting tube 57 supported in the back head member and supplied with liquid through a gland member 58 in the usual manner. The water supply connection is illustrated at 59 and liquid is conducted through the cylinder head member by means of a suitable passage, a part of which is shown at 60. Formed on the valve chest section opposite from the throttle valve is a lateral boss 61 in which is secured the rotation handle 62. This rotation handle according to common practice is hollow and provided with a lubricant chamber for supplying lubricant to the machine through a passage 63.

The operation of my improved drilling mechanism will be readily apparent in view of the above description. Motive fluid is supplied to the inlet passage 50 when the throttle valve is opened and thence to the annular inlet grooves 25 and 26. When the parts are in the position illustrated in Fig. 1, fluid under pressure is flowing from the inlet groove 26 to the rear end of the cylinder

der. The forward end of the cylinder is at this time open to exhaust through passages 29 and 30, and annular groove 31 and groove 32 in the valve, through annular exhaust groove 33 and exhaust port 34. The hammer piston is driven forwardly and imparts a blow to the hammer drill steel through the tappet 14. On the forward stroke of the piston, when the throw passages 35 are uncovered, pressure fluid is transmitted from the cylinder through these passages to the bore 21 rearwardly of flange 23 in the valve chest and since the area thus exposed to pressure is much larger than the opposing areas subjected to pressure, the valve is thrown forwardly to the position shown in Fig. 2. The piston also overruns the exhaust port 44 and most of the pressure fluid in the rear end of the cylinder is exhausted through this port. After the piston strikes a blow, it will rebound sufficiently to uncover the supply passages 29 and 30 and pressure fluid is thus admitted to the forward end of the cylinder from the inlet groove 25 around grooves 32 in the valve and 31 in the valve chest to passages 29 and 30. The piston is thus driven rearwardly and during the rearward stroke the ratchet mechanism holds the rifle bar against rotation and a rotative movement is imparted to the drill steel in a well known manner. After the exhaust port 44 and throw passages 35 are covered on the rearward stroke of the piston, a certain amount of air is trapped in the rear end of the cylinder and this air will be highly compressed when the piston approaches the rear end of its stroke and this compression pressure acting on the forward end of the valve and shoulder 43 acts to throw the valve rearwardly and again open communication between the supply and the rear end of the cylinder around the end of the valve. The fluid which has been supplied through the throw passages 35 to bore 21 for throwing the valve forwardly has practically all been exhausted through the exhaust ports 34 as will be readily seen in Fig. 2, and the only opposing pressure which the compression pressure has to oppose in throwing the valve is the constant pressure acting on the shoulder 36. The valve is held in its rearward position on the forward stroke of the piston by live pressure acting on the end area of the valve and the shoulder 43, and the valve is probably not thrown until this pressure is somewhat relieved by uncovering of the exhaust port 44.

It will be noted that the movement of the valve is limited in both instances by the large annular flange 23 intermediate the ends of the valve. When the valve is thrown rearwardly, this flange abuts against a stop on the member 40, and when it is thrown forwardly abuts against a stop provided by the flange between groove 31 and bore 21. This avoids the necessity of providing end buffers for the valve and thereby eliminates any obstruction in the axial passage leading to the rear end of the cylinder.

The general construction and operation of the modification illustrated in Fig. 7 is very similar to that which has just been described in connection with the stopper drill. However, instead of the valve chest being formed in a separate member which abuts against the end of the cylinder, it is formed in a member 64 which is mounted in a counterbore 65 formed in an enlargement of the cylinder. The rifle bar and ratchet mechanism are also mounted between members 66 and 67 which are housed in the bore 65. A head construction generally designated 68

takes the place of the intermediate head construction and feed cylinder in the stoper drill and the throttle valve is in this instance carried by the rear head section. Motive fluid is conducted from the throttle valve through a longitudinally extending passage 70 which extends through members 66, 67 and 64 and opens into the annular inlet groove 71 by a radial passage 72. In this instance the forward end spool 24 of the valve is made somewhat shorter and the partition in the inlet chamber left out. This shortens the construction to some extent, but otherwise the operation of the valve mechanism is exactly the same as in the stoper valve construction. The shoulder 36 presenting the rearwardly facing constant pressure area, communicates with the inlet passage 70 by a short diagonal passage 73. The other parts of this valve mechanism and the supply passages are given the same numbers as in Figs. 1 to 6 and the operation of the mechanism will not be repeated since it is obviously practically the same as in Figs. 1 to 6.

As a result of my invention, it will be evident that I have devised an improved streamline design for a rock drilling apparatus employing a tubular distribution valve of novel construction surrounding the rifle bar; that this valve mechanism provides means permitting a direct axial unrestricted flow of motive fluid to the cylinder on its power stroke; that these desirable features have been incorporated in a novel stoper construction having a valve chest section in axial alinement with the hammer motor in which may be mounted the throttle valve and rotation handle in a compact arrangement.

While I have in this application specifically described two embodiments which my invention may assume in practice, it will be understood that these forms of the same are shown for purposes of illustration, and that the invention may be modified and embodied in various other forms without departing from its spirit or the scope of the appended claims.

What I claim as new and desire to secure by Letters Patent is:

1. In a rock drill, a pressure fluid actuated percussive motor comprising a cylinder, a piston reciprocable therein, fluid distribution means for said motor including a valve chest in longitudinal alinement with said cylinder, a tubular valve reciprocable longitudinally in said valve chest and comprising an imperforate sleeve open from end to end, said valve having an area within the interior thereof and facing forwardly and in constant communication with the rear end of the cylinder whereby the valve is thrown in the rearward direction by compression pressure built up in the rear end of the cylinder on the return stroke of the piston, means for throwing the valve in the opposite direction comprising an annular shoulder on said valve presenting a rearwardly facing area, means for subjecting the latter area to intermittent pressure, and means for subjecting a second rearwardly facing area on the exterior of said valve to constant pressure.

2. In a rock drill, a pressure fluid actuated percussive motor comprising a cylinder, a piston reciprocable therein, and fluid distribution means for said motor including a valve chest in longitudinal alinement with said cylinder and having an annular inlet chamber at one end thereof, a longitudinally reciprocable tubular valve in said valve chest having internal bores of different diameter to provide a surface facing forwardly and

constantly communicating with the rearward end of said cylinder and a plurality of other radially extending surfaces, said valve chest having a radially extending partition in said inlet chamber for guiding one end of said tubular valve, and means for subjecting said other radially extending surfaces to pressure fluid.

3. In a rock drill, a pressure fluid actuated percussive motor comprising a cylinder, a piston reciprocable therein, fluid distribution means for said motor including a valve chest in longitudinal alinement with said cylinder having an annular inlet chamber at the forward end thereof, said inlet chamber comprising two annular grooves divided by a partition, and a tubular valve reciprocable longitudinally in said valve chest, said valve having an end spool controlling admission of motive fluid from said inlet chamber to opposite ends of said cylinder, said partition cooperating with said end spool to guide the end of said valve.

4. In a rock drill, a pressure fluid actuated percussive motor comprising a cylinder, a piston reciprocable therein, fluid distribution means for said motor including a valve chest in longitudinal alinement with said cylinder having an inlet chamber at the forward end thereof communicating directly with the rear end of said cylinder by a short axial passage of comparatively large diameter, and a longitudinally reciprocable tubular valve in said valve chest and comprising an imperforate sleeve open from end to end, said valve having a forward end spool controlling admission of pressure fluid from said inlet chamber to opposite ends of the cylinder, said end spool being of the same diameter as said passage which leads from the inlet chamber to the rear end of said cylinder and adapted to be received in said passage to cut off supply of motive fluid to the rear end of the cylinder, said valve having at its rear end a sleeve of reduced diameter slidably in a reduced bore of said chest and presenting a rearwardly facing area upon which fluid pressure constantly acts.

5. In a rock drill, a pressure fluid actuated percussive motor comprising a cylinder, a piston reciprocable therein, means for closing the rear end of said cylinder including a longitudinally abutting member, fluid distribution means for said motor including a valve chest formed in said member in longitudinal alinement with said cylinder and having an annular inlet chamber at its forward end communicating with the rear end of said cylinder by a relatively large direct axial passage, a fluid actuated tubular valve reciprocable in said valve chest, said tubular valve being of greater internal diameter at its forward end than at its opposite end whereby a forwardly facing surface is provided within the interior of said valve, and said valve having a forward end spool controlling admission of motive fluid from said inlet chamber to opposite ends of the cylinder, means for positioning said valve to effect its different controlling functions, a throttle valve mounted on said member adjacent said inlet chamber, and a relatively short direct radial supply passage leading from said throttle valve to said inlet chamber.

6. In a rock drill, the construction defined in claim 5 wherein there is further provided a radial flange forming a partition in said inlet chamber for guiding the forward end of said valve and a portion of said flange being cut away.

7. A pressure fluid motor comprising a cylinder, a piston reciprocable therein, fluid distribution means for effecting reciprocation of said pis-

- ton comprising a reciprocable differential valve having an end area in constant communication with the rear end of the cylinder whereby the valve is thrown rearwardly by compression pressure built up in the rear end of the cylinder on the return stroke, means for throwing said valve forwardly comprising a rearwardly facing area on the exterior of said valve subjected to constant pressure and a second rearwardly facing area adapted to be subjected to intermittent pressure, and means for limiting the movement of said valve in a forward direction comprising an annular flange disposed intermediate the ends of said valve and a cooperating annular stop flange in said valve chest.
8. A pressure fluid motor comprising a cylinder, a piston reciprocable therein, fluid distribution means for effecting reciprocation of said piston comprising a valve chest in longitudinal alignment with said cylinder, a reciprocable differential valve in said valve chest and comprising an imperforate sleeve open from end to end, said valve having an area within the interior thereof and facing forwardly and in constant communication with the rear end of the cylinder whereby the valve may be thrown rearwardly by compression of the fluid which is trapped in the rear end of the cylinder at the time of closing of the exhaust, and means for throwing the valve in the opposite direction including a rearwardly facing area adapted to be subjected to intermittent pressure and an area disposed rearwardly of said latter area and subjected to constant fluid pressure.
9. In a rock drilling apparatus, a pressure fluid motor comprising a cylinder, a piston reciprocable therein, fluid distribution means for effecting reciprocation of said piston comprising a valve chest in longitudinal alignment with said cylinder, a tubular valve reciprocably mounted in said valve chest and comprising an imperforate sleeve open from end to end, said valve having an end spool for controlling admission of motive fluid to opposite ends of the cylinder, means on said valve presenting a forwardly facing area in communication with the rear end of the cylinder whereby said valve may be thrown by compression of fluid trapped in the rear end of said cylinder, means for throwing said valve in the opposite direction including an annular shoulder adjacent the rear end of said valve, means for subjecting a rearwardly facing area on said shoulder to constant pressure, and a tubular guiding portion on said valve projecting rearwardly beyond said shoulder.
10. In a pressure fluid motor, a cylinder, a piston reciprocable therein, and fluid distribution means for said cylinder to effect reciprocation of said piston including a valve chest having a valve chamber aligned with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, said valve having a plurality of pressure areas including a pressure area within said valve subjected continuously to the pressure in one end of said cylinder, and means for subjecting others of said pressure areas to pressure fluid to control the positioning of said valve.
11. In a pressure fluid motor, a cylinder, a piston reciprocable therein, and fluid distribution means for said cylinder to effect reciprocation of said piston including a valve chest having a valve chamber aligned with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, the imperforate sleeve-like portion of said valve surrounding a chamber having constant communication in all positions of said valve with said passage, a passage leading from said second mentioned groove to the forward end of the cylinder for supplying fluid to the forward end of the cylinder when said valve is in its forward position, said valve having a plurality of pressure areas including the rear pressure area on said flange, and a plurality of passages for conducting pressure fluid to said pressure areas for positioning said valve including a piston controlled passage leading from the cylinder to the larger bore at the rear side of said flange for admitting fluid from the cylinder to the rear pressure area on said flange to throw said valve into its forward position.
12. In a pressure fluid motor, a cylinder, a piston reciprocable therein, and fluid distribution means for said cylinder to effect reciprocation of said piston including a valve chest having a valve chamber aligned with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the small-

- er bore, said sleeve-like portion providing a forward pressure area and said valve providing another forwardly facing annular pressure area within the interior thereof, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, said valve having a plurality of pressure areas including the rear pressure area on said flange, and a plurality of passages for conducting pressure fluid to said pressure areas for positioning said valve including a piston controlled passage leading from the cylinder to the larger bore at the rear side of said flange for admitting fluid from the cylinder to the rear pressure area on said flange to throw said valve into its forward position, said valve being thrown into its rearward position by compression pressure built up in the rear end of the cylinder during the rearward piston stroke and acting on the forward pressure areas on the forward end of said sleeve-like portion of the valve and within the interior of the latter respectively.
13. In a pressure fluid motor, a cylinder, a piston reciprocable therein, and fluid distribution means for said cylinder to effect reciprocation of said piston including a valve chest having a valve chamber alined with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, said valve being thrown into its rearward position by compression pressure built up in the rear end of the cylinder during the rearward piston stroke and acting on the forward pressure area on the forward end of said sleeve-like portion of the valve, and a passage for supplying fluid from the source of fluid supply to a rearward pressure area on the valve for constantly urging the valve toward its forward position.
15. In a pressure fluid motor, a cylinder, a piston reciprocable therein, and fluid distribution means for said cylinder to effect reciprocation of said piston including a valve chest having a valve chamber alined with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage leading from said second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, and a passage for supplying fluid from the source of fluid supply to a rearward pressure area on the valve for constantly urging the valve toward its forward position.

- second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, and an exhaust passage connecting the larger bore at the forward side of the flange directly to atmosphere for conducting fluid from said second mentioned groove to exhaust when said valve is in its rearward position.
16. In a pressure fluid motor, a cylinder, a piston reciprocable therein, and fluid distribution means for said cylinder to effect reciprocation of said piston including a valve chest having a valve chamber alined with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, a passage for supplying fluid from the source of fluid supply to a rearward pressure area on the valve for constantly urging the valve toward its forward position, and an exhaust passage connecting the larger bore at the forward side of the flange directly to atmosphere for conducting fluid from said second mentioned groove to exhaust when said valve is in its rearward position.
17. In a pressure fluid motor, a cylinder, a piston reciprocable therein, and fluid distribution means for said cylinder to effect reciprocation of said piston including a valve chest having a valve chamber alined with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, said valve being thrown into its rearward position by compression pressure built up in the rear end of the cylinder during the rearward piston stroke and acting on the forward pressure areas on the forward end of said sleeve-like portion of the valve and within the interior of the latter respectively, and an exhaust passage connecting the larger bore at the forward side of the flange directly to atmosphere for conducting fluid from said second mentioned groove to exhaust when said valve is in its rearward position.
18. In a pressure fluid motor, a cylinder, a piston reciprocable therein, and fluid distribution means for said cylinder to effect reciprocation of said piston including a valve chest having a valve chamber alined with the cylinder axis, said valve chamber having relatively large and small bores, a fluid supply groove communicating with the smaller bore, a groove communicating with the smaller bore and located between said fluid supply groove and the larger bore, an automatic fluid distributing valve reciprocably mounted in said valve chamber and having a large flange fitting the larger bore and a forwardly projecting imperforate sleeve-like portion fitting the smaller bore, said sleeve-like portion having a peripheral groove for connecting said fluid supply groove and said second mentioned groove in communication when the valve is in its forward position and for cutting off such communication when the valve is in its rearward position, a passage connecting said smaller bore with the rear end of the cylinder and communicating with said smaller bore when the valve is in its rearward position to admit fluid from said supply groove to the rear end of the cylinder and said sleeve-like portion cutting off such communication through said passage when the valve is in its forward position, a passage leading from said second mentioned groove to the forward end of the cylinder for supplying fluid to the forward end of the cylinder when said valve is in its forward position, a piston controlled passage leading from the cylinder to the larger bore at the rear side of said flange for admitting fluid from the cylinder to the rear pressure area on said flange to throw said valve into its forward position, said valve

- being thrown into its rearward position by compression pressure built up in the rear end of the cylinder during the rearward piston stroke and acting on the forward pressure area on the forward end of said sleeve-like portion of the valve, a passage for supplying fluid from the source of fluid supply to a rearward pressure area on the valve for constantly urging the valve toward its forward position, and an exhaust passage connecting the larger bore at the forward side of the flange directly to atmosphere for conducting fluid from said second mentioned groove to exhaust when said valve is in its rearward position. 5 80 85 90 95 100 105 110 115 120 125 130 135 140 145 150
19. In a pressure fluid motor, a cylinder, a piston reciprocable therein, fluid distribution means for said cylinder to effect reciprocation of said piston including a valve chest having a valve chamber alined with the cylinder axis, said valve chamber having relatively large and small bores, a fluid supply passage communicating with the smaller bore at the forward end thereof, a passage communicating with the smaller bore between said supply passage and said larger bore for conducting fluid to the forward end of the cylinder, an exhaust passage communicating with the larger bore, a piston controlled passage leading from the cylinder to the larger bore at the rear of said exhaust passage, a passage connecting the smaller bore with the rear end of the cylinder, and an automatic fluid distributing valve reciprocably mounted in said valve chamber, said valve comprising a hollow sleeve open from end to end and having an enlarged radial flange adjacent the rear end thereof and a forwardly projecting sleeve-like portion, said flange fitting the larger bore and said sleeve-like portion fitting the smaller bore, said valve being thrown into its rearward position by compression pressure built up within the rear end of the cylinder during the rearward piston stroke and transmitted to the forward pressure area on said sleeve-like portion through said fifth mentioned passage and when in said rearward position cutting off communication of said second passage with said fluid supply passage, opening communication between said second passage and said exhaust passage and opening communication between the rear end of the cylinder and the fluid supply passage through said fifth passage, said valve being thrown into its forward position by pressure conducted from said cylinder through said fourth mentioned passage to the rear pressure area on said flange and when in said forward position opening communication between said supply passage and said second passage and said exhaust passage and cutting off communication of the smaller bore with the rear end of the cylinder through said fifth mentioned passage, and a rearward pressure area on said valve at the rear of said flange and a passage connecting the fluid supply passage with said pressure area for constantly urging said valve toward its forward position. 15 20 25 30 35 40 45 50 55 60 65 70 75
21. In a pressure fluid motor, a cylinder, a piston reciprocable therein, and fluid distribution means for effecting reciprocation of said piston including a valve chest having relatively large and small bores, a fluid supply passage communicating with the smaller bore, a passage communicating with the smaller bore between said fluid supply passage and said larger bore for supplying fluid to the forward end of the cylinder, an exhaust passage communicating with the larger bore, a passage communicating with the smaller bore for supplying fluid to the rear end of the cylinder, and an automatic fluid distributing valve reciprocably mounted in the valve chest and comprising a hollow imperforate sleeve open from end to end and having an enlarged flange fitting the larger bore and a forwardly extending sleeve-like portion fitting the smaller bore, said sleeve having bores of different diameters to provide a radially extending surface and said bores having constant communication with one end of the motor cylinder, said valve when in its forward position cutting off communication between said supply passage and said fourth mentioned passage, opening communication between said supply passage and said second mentioned passage and cutting off communication between said second mentioned passage and said third mentioned passage, and said valve when in its rearward position opening communication between said supply passage and the rear end of the cylinder through said fourth mentioned passage, cutting off communication between said supply passage and said second mentioned passage and connecting said second mentioned passage with said exhaust passage, said valve having a plurality of pressure areas, and a plurality of passages for conducting pressure fluid to said pressure areas for positioning said valve. 150

22. In a pressure fluid motor, a cylinder, a piston reciprocable therein and fluid distribution means for effecting reciprocation of said piston including a valve chest having relatively large and small bores, a fluid supply passage communicating with the smaller bore, a passage communicating with the smaller bore between said supply passage and said larger bore for supplying fluid to the forward end of the cylinder, an exhaust passage communicating with the larger bore, a passage communicating with the smaller bore for supplying fluid to the rear end of the cylinder, a piston controlled passage for supplying pressure fluid from the cylinder to the larger bore, and an automatic fluid distributing valve reciprocably mounted in said valve chest and comprising a hollow imperforate sleeve open from end to end and having an enlarged flange fitting the larger bore and a forwardly extending sleeve-like portion fitting the smaller bore, said valve having in the same transverse zone with said enlarged flange an internal forwardly facing surface, said valve being thrown into its forward position by pressure fluid conducted from the cylinder through said fifth mentioned passage to the larger bore to act on the rear pressure area of said flange, said valve having a second rear pressure area, a passage for conducting pressure fluid to said last mentioned pressure area for holding said valve in its forward position, said valve being thrown into its rearward position by compression built up in the rear end of the cylinder during the rearward stroke of the piston and acting on the forward pressure area of said sleeve-like portion and on said internal forwardly facing surface, said valve when in its forward position cutting off communication between the smaller bore and said fourth mentioned passage, opening communication between said supply passage and said second mentioned passage and cutting off communication between said second mentioned passage and said exhaust passage, and when in its rearward position opening communication between said smaller bore and the rear end of the cylinder through said fourth mentioned passage, cutting off communication between said supply passage and said second mentioned passage and opening communication between said second mentioned passage and said exhaust passage.
23. In a pressure fluid motor, a cylinder, a piston reciprocable therein, and fluid distribution means for effecting reciprocation of said piston including a valve chest having relatively large and small bores, a fluid supply passage communicating with the smaller bore, a passage communicating with the smaller bore between said supply passage and the larger bore for supplying fluid to the forward end of the cylinder, an exhaust passage communicating with the larger bore, a passage connecting the smaller bore with the rear end of the cylinder for supplying fluid to the rear end of the cylinder, a piston controlled passage leading from the cylinder to said larger bore, an automatic fluid distributing valve reciprocably mounted in the valve chest and comprising a hollow imperforate sleeve open from end to end and having an enlarged flange fitting the larger bore, a forwardly extending sleeve-like portion fitting the smaller bore and a rearwardly extending guide sleeve, a passage for supplying fluid from said fluid supply passage to the rear pressure area on said rearwardly extending guide sleeve for constantly urging said valve toward its forward position, said valve being thrown into its forward position by said constant pressure and the pressure of the fluid supplied through said fifth mentioned passage to said larger bore to act on the rear pressure area of said flange, and said valve being thrown into its rearward position by compression pressure built up in the rear end of the cylinder during the rearward piston stroke and acting on the forward pressure area of said sleeve-like portion, said valve when in its forward position cutting off communication between said smaller bore and the rear end of the cylinder through said fourth mentioned passage, opening communication between said supply passage and said second mentioned passage and cutting off communication between said second mentioned passage and said exhaust passage, and said valve when in its rearward position opening communication between said smaller bore and the rear end of the cylinder for supplying fluid from said supply passage through said fourth mentioned passage to the rear end of the cylinder, cutting off communication between said supply passage and said second mentioned passage and opening communication between said second mentioned passage and said exhaust passage.
24. A pressure fluid motor including a cylinder, a piston reciprocable in the cylinder, and fluid distribution means for effecting reciprocation of said piston including means forming a valve chamber having a plurality of bores of different sizes, a hollow valve reciprocable in said valve chamber and having portions cooperating with said different bores, means for conducting live pressure fluid to said valve chamber, means for connecting longitudinally spaced portions of said valve chamber with an end of the cylinder and an intermediate point in the latter, and a valve having a surface on which line pressure acts continuously, a larger opposed surface formed at least in part within the interior of said valve and on which line pressure acts during admission to the above mentioned end of the cylinder to effect strokes of said piston in one direction, and a still larger surface facing similarly to the first mentioned surface to which pressure is admitted when said piston reaches in said strokes said intermediate point in the cylinder.
25. A pressure fluid motor including a cylinder, a piston reciprocable in the cylinder, and fluid distribution means for effecting reciprocation of said piston including means forming a valve chamber having a plurality of bores of different sizes, a hollow valve reciprocable in said valve chamber and having portions cooperating with said different bores, means for conducting live pressure fluid to said valve chamber, means for connecting the valve chamber to opposite ends of the cylinder and to a point intermediate the ends of the cylinder, and means for connecting the valve chamber to atmosphere, said valve having an outer surface on which live pressure acts continuously, a larger opposed surface formed at least in part within the interior of said valve and on which live pressure acts at the beginning and during a portion of each stroke of the piston in one direction, and a still larger surface facing similarly to the first surface to which pressure is admitted adjacent the end of such strokes.

ELMER G. GARTIN.

CERTIFICATE OF CORRECTION.

Patent No. 1,929,420.

October 10, 1933.

ELMER G. GARTIN.

It is hereby certified that error appears in the printed specification of the above numbered patent requiring correction as follows: Page 1, line 8, for "stopper" read stoper; and line 105, for "the" second occurrence read to; page 2, line 142, for "stopper" read stoper; page 4, line 1, claim 7, after "valve" insert the words comprising an imperforate sleeve open from end to end and; and page 6, line 45, claim 16, for "positon" read position; and that the said Letters Patent should be read with these corrections therein that the same may conform to the record of the case in the Patent Office.

Signed and sealed this 30th day of October, A. D. 1934.
